ALFRED J. CHAMBERLAIN, OF MILWAUKEE, WISCONSIN

CONTAINER CLOSING MACHINE

Application filed October 6, 1927. Serial No. 224,330.

This invention relates in general to a closing machine for containers of the type which may be manually shifted from container to container and which is operated on each container to bend in an appropriate manner securing elements provided for the purpose of fastening and sealing a cover or closure to the container.

One of the objects of the present invention is to provide a portable closing machine of this character which has common means for shifting the machine from container to container and for operating the bending means or dies which are provided for bending the securing elements. The operating means is so organized with the bending means that it operates the same with marked mechanical advantage, thereby exerting a powerful bending action without the exercise of any appreciable degree of strength or effort on the part of the operator.

Another object of the invention is to provide a container closing machine of this character which has a plurality of sets of dies which subject each securing element to a series of successive bending operations whereby to cause the securing elements to fasten the cover or closure in closed position.

The machine embodying the present invention is especially adapted for use with a container which has a circumferential series of vertical securing lugs around the periphery of its opening. These lugs are adapted to be bent around the rim of the closure and to effect this the machine embodying the present invention has a series of horizontally disposed sliding dies which are influenced by an actuating member to bend the lugs from their vertical position to a horizontal position. The actuating member carries a die which bends the lugs from a horizontal position to their final securing position. Organized with the dies is a plurality of anchoring jaws which grip the container at the very start of the operation so as to hold the closure in position and also to maintain the machine in position. These anchoring jaws are automatically set and released upon appropriate operation of the dies.

Other objects and advantages reside in cer-

tain novel features of the construction, arrangement and combination of parts which will be hereinafter more fully described and particularly pointed out in the appended claims, reference being had to the accompanying drawings forming a part of this specification, and in which:

Figure 1 is a view in vertical section taken on line 1—1 of Figure 2, parts being shown in side elevation for the sake of illustration;

Figure 2 is a plan view of the machine, the handles being shown in section;

Figure 3 is a fragmentary view in section taken on line 3—3 of Figure 1;

Figure 4 is a plan view showing diagrammatically one type of container with which the machine may be used; and

Figure 5 is a fragmentary sectional view showing how the dies are positioned in the final phases of the operation.

Referring to the drawings, the numeral 1 designates a container having an inclined gasket seat 2 and a rim 3. Bendable securing lugs 4 are integral with the container and project vertically upward therefrom prior to the application of the cover or closure 5 to the container. The cover or closure 5 has a rolled rim 6 and an inclined portion 7 which compresses a gasket 8 against the gasket seat 2.

The present invention provides a machine for bending the lugs 4 from their vertical position, shown in Figure 1, around to the dotted line position, shown in Figures 1 and 4, and for this purpose the machine comprises a base 10 having a depending peripheral flange 11 adapted to engage the closure or cover 5 as shown in Figure 1. Sockets 12 are integrally formed with the base and receive sliding dies 13. The dies are hollowed out to receive portions of the coil springs 14 which tend to project the dies outwardly. These dies 13 have curved lug engaging members 15 and above the lug engaging members have inclined or camming surfaces 16. An actuating member designated generally at 17 is provided for the dies 13 and includes a ring-like body portion 18 integral with the outer ends of spider arms 19, the spider arms 19 radiating from a hub or bearing portion 20 which is slidably fitted

on a fixed mounting shaft 21 fastened to the base 10 as indicated at 22. The ring-like body portion 18 of the actuating member has an inclined or camming surface 23 which engages and coacts with the inclined or camming surfaces 16 of the dies 13 to force these dies 13 inwardly against the action of the springs 14 when the actuating member is depressed or moved downwardly. The inward movement 10 of the dies 13 bend the lugs 4 from their vertical position, shown in Figure 1, to the horizontal position indicated in dotted lines in the same figure. After this bending of the lugs has been completed the dies 13 have been moved inwardly clear of the lugs 4 and an annular die member 24 formed at the lower end of the ring-like body portion 18 of the actuating member then engages the lugs 4 to force them down into their final securing position, as illustrated in Figure 5.

Common means is provided for appropriately moving the actuating member and for handling and shifting the machine from one container to another and this means comprises a pair of racks 25 provided on the shaft 21. Pinions 26 mesh with the racks 25, the pinions 26 being fitted in slots 27 provided in the hub or bearing portion 20 of the actuating member and being pivoted to this hub 25 or bearing portion as indicated at 28. Elongated handles 29 are rigidly connected with the pinions 26 as indicated at 30.

The upward movement of the actuating member on the shaft 21 is limited by a stop pin 31 provided on the shaft 21 and engageable with the hub or bearing portion 20 of the actuating member. The downward movement of the actuating member is limited by the means of adjustable stop screws 32 threaded through lugs 33 integral with the ring-like body portion 18 of the actuating member and held in adjusted position by means of nuts 34. The lower ends of the stop screws 32 are engageable with the base 10 in between 40 the sockets 12, as will be understood from Figure 2.

Means is provided for anchoring the machine on the container at the very start of the operation and this means is operated automatically so as to be engaged at the start of the operation and disengaged when the operation has been completed and when the machine is to be removed from the container. This anchoring means comprises a plurality of jaws 40 pivoted as at 41 on the periphery of the base 10 and adapted to engage around the rim 3 of the container. The jaws 40 have tail pieces 42 projecting in under the base 10 through openings in its flange 11 and connected to studs or bolts 43, the studs or bolts 43 projecting through oblong openings 44 provided in the base 10 and being urged upwardly by means of coil springs 45 interposed between a washer 46 engaging the head of the stud 43 and a washer 47 mounted on the stud

and overlapping the margin of the opening 44. These springs 45 are tensioned so as to tend at all times to swing the jaws 40 to a position wherein they engage the rim of the container. Links in the form of I-bolts 50 are pivotally connected as at 51 to the jaws 40 and project through apertured lugs 52 provided on the ring-like body portion 18 of the actuating member. Nuts 53 threaded on the upper ends of the links 50 are engageable with these lugs 52. When the handles 29 are released or raised upwardly the actuating member moves upwardly and the links 50 are elevated due to the engagement of the lugs 52 with the nuts 53 thereof whereby the jaws 40 are swung outwardly against the action of the springs 45. As soon as the handles 29 are spread apart and downwardly from their extreme upper position the lugs 52 move downwardly and permit the links 50 to move downwardly and the jaws 40 to swing inwardly under the influence of the springs 45.

In using the machine, the handles 29 are grasped and the machine is lifted and placed on top of the container. Then after the handles are moved apart or released the springs 45 cause the jaws 40 to engage the rim 3 of the container. The machine is then releasably locked on the container, the base 10 of the machine and the shaft 21 being fixed relative to the container. The flange 11 of the base 10 holds the cover of the container in position. The handles 29 are then forced outwardly and downwardly and the pinions 26 roll down the racks 25 and force the actuating member 17 downwardly. Due to the length of the handles the movement imparted to these handles is transmitted with mechanical advantage to the actuating member. As the actuating member moves downwardly it first forces the dies 13 inwardly to bend the lugs 4 over to a horizontal position, this inward movement of the dies 13 being accomplished by the coaction of the inclined or camming surfaces 16 and 23. After this, the die 24 of the actuating member engages the lugs 4 and forces them down to the final closing position illustrated in Figure 5. The handles 29 are then elevated and the mere act of elevating the handles and lifting the machine by the handles automatically disengages the jaws 40 from the rim of the container. The dies 13 are restored to their outer positions by the springs 14. Even in its extreme upper position the camming surface 23 still engages the inclined surfaces 16 to prevent displacement of the dies 13 from the socket 12.

An important feature of the invention is believed to reside in the novel operating mechanism constituted by the handles 29 and their associated parts. This operating mechanism performs the two functions of facilitating the manipulation of the machine and the operation of the bending means or dies.

It also operates the anchoring means. This feature is not restricted in its application to the particular die means shown nor to use with anchoring means.

5. The invention claimed is:

1. A machine for securing a cover to a container by appropriately bending securing elements and comprising a base, dies slidable on the base for initially bending the securing elements, an actuating member for the dies, cooperating means between the dies and actuating member for imparting operative movement to the dies when the actuating member is appropriately moved, and a die 10 on the actuating member for imparting final bending movement to the securing elements.

2. A machine for securing a closure to a container by appropriately bending securing elements and comprising a base having sockets, dies slidable in the sockets of the base and adapted to initially bend the securing elements, springs for projecting the dies, an actuating member for the dies, cooperating camming surfaces between the actuating member and the dies for imparting operative movement to the dies when the actuating member is appropriately moved, and a die 25 on the actuating member for imparting final bending movement to the securing elements.

3. A machine for applying a closure to a container by appropriately bending securing elements and comprising a base, bending means for the securing elements mounted on the base and means for positively anchoring the base to the container during the bending operation.

4. A machine for applying a closure to a container by appropriately bending securing elements and comprising a base, bending means for the securing elements mounted on the base and means for anchoring the base to the container during the bending operation, and comprising jaws pivoted to the base and 40 engageable with the container, springs for urging the jaws to a position wherein they engage the container, and means for automatically releasing the jaws.

5. A machine for securing a closure to a container by appropriately bending securing elements and comprising a base, bending means for the securing elements mounted on the base, an actuating member for said bending means, anchoring means securing the base 55 to the container and comprising a plurality of anchoring jaws, spring means for moving the jaws to a position to have securing engagement with the base, and means connecting the jaws and actuating member whereby 60 when the actuating member is retracted to inactive position the jaws will be released.

6. A machine for applying a cover to a container comprising a base engageable with the cover, releasable securing means on the base 65 engageable with the container to fasten the

base in position thereon, a die on the base for causing the parts of the cover and container to engage, and common means for operating the die and for causing the securing means to have fastening engagement with the container and also to be released from the container at the proper times.

7. A machine for securing a closure to a container by appropriately bending securing elements and comprising a set of dies movable transversely of the container and operable to initially bend the securing elements, and die means movable longitudinally of the container for finally and completely bending the securing elements to securing position.

8. A machine for securing a cover to a container by appropriately bending securing elements and comprising a base engageable with the cover, dies slidable across the base and transversely of the cover and operable to initially bend the securing elements, an actuating member movable longitudinally of the container and coacting with the sliding dies for imparting transverse movement thereto, and a die carried by the actuating member and partaking of its longitudinal movement and engageable with the securing elements after they have been initially bent by the sliding dies and operating to complete the bending of the securing elements.

9. A machine for securing a closure to a container by appropriately bending the securing elements and comprising a base, dies slidable across the base and transversely of the securing elements, an actuating member mounted on the base for movement longitudinally of the container, cooperating camming means on the dies and on the actuating member for imparting transverse sliding movement to the dies when the actuating member is moved longitudinally whereby the dies initially bend the securing elements, and a die carried by the actuating member and engagable with the securing elements after the sliding dies have completed the initial bending thereof and operating to completely and finally bend the securing elements as the actuating member completes its longitudinal movement.

10. A machine for applying a closure to a container by appropriately bending securing elements and comprising a base, bending means for the securing elements mounted on the base, operating means for the bending means, means for positively anchoring the base to the container during bending operation, and means actuated from the operating mechanism for automatically applying and releasing the anchoring means.

11. A machine for securing a closure to a container by appropriately bending securing elements and comprising a base engageable with the closure, dies slidable transversely of the base and operable to initially bend the securing elements, a ring-like actuating
